UNITED STATES PATENT OFFICE.

JOHN C. KNAPP, JR., OF PHILADELPHIA, PENNSYLVANIA.

PIPE-MOLD.

986,068.

Specification of Letters Patent. Patented Mar. 7, 1911.

Application filed March 22, 1909. Serial No. 485,009.

To all whom it may concern:

Be it known that I, JOHN C. KNAPP, Jr., a citizen of the United States, residing at Philadelphia, in the county of Philadelphia and State of Pennsylvania, have invented a new and useful Pipe-Mold, of which the following is a specification.

It is the object of the present invention to provide a simple and durable culvert mold 10 which will be capable of withstanding a maximum degree of pressure and which may be readily removed when the material which is packed around it has become hardened.

It is customary, in most instances, to provide a culvert mold of this class in which the wall of the mold is comprised of but a single sheet of metal bent into substantially cylindrical form and with its opposite longitudinal edges overlapped. It has been found 20 however, by practical experience, that a mold of this construction is frequently difficult to remove from the mass of material owing to the fact that all portions of its walls are not simultaneously adjusted to the 25 same degree.

It is therefore the object of the present invention to provide a mold of this class so constructed that after the material, packed around the mold, has hardened, it may be 30 readily collapsed or contracted and withdrawn from the material or partially completed culvert.

In the accompanying drawings, Figure 1 is a vertical longitudinal sectional view of a 35 mold constructed in accordance with the present invention. Fig. 2 is a vertical transverse sectional view through the mold on the line 2—2 of Fig. 1, and, Fig. 3 is a detail view partly in elevation and partly in section showing the manner of supporting the mold section from the adjusting rod or shaft of the mold.

As heretofore stated, the mold embodying the present invention is made up of a plurality of arcuate sections and while, in the drawings, these sections are shown as four in number, it will be understood that any desired number may be employed.

Each of the sections extends through an 50 arc of substantially 90° and consists of a sheet metal plate 5 rolled or curved to the degree stated and held yieldably in this shape or position through the medium of ribs which are secured upon its inner surface 55 and which extend from one longitudinal edge to the other thereof. Each of the

ribs just mentioned embodies a wing 6 through which and the said plate 5 are passed suitable securing devices 7 for the purpose of securing the rib in position upon the said plate, and a rib 8 which extends inwardly radially at right angles from the rib 6 and serves as a means for the attachment of suitable adjusting and supporting devices which will presently be fully described. 65

As shown in Fig. 2 of the drawings, each of the upper ones of the plate 5, indicated more specifically by the numeral 5^a, has its edge portions offset as at 9 to afford side flanges and in assembling this section with the two side sections of the mold, indicated each specifically by the reference character 5^b, these flanges 9 or off-set edge portions overlap the upper edge portions of said sides, as clearly shown in the said Fig. 2 of the drawing. Similarly, the lower edge portions of the side sections 5^b are off-set, as at 10 and overlap the side edges of the bottom section of the mold, indicated specifically by the reference character 5^c, it being understood that all of the sections when assembled in the manner stated, afford a cylindrical core, the outer surface of which is practically unbroken and smooth. 70 75 80

As clearly shown in Fig. 2 of the drawings, there are formed or secured at both ends of the several flanges 8 of the section 5^a, extensions 11 which overlap the opposed ends of the corresponding flanges of the sections 5^b and these sections 5^b are provided also at their lower ends with similar extensions 12 which overlap the extremities of the corresponding flanges 8 of the bottom section 5^c of the mold, it being understood that by this means, relative longitudinal movement of the mold section is effectually obviated. Furthermore, in this connection, it will be observed upon inspection of Fig. 1 of the drawings that the flanges or ribs of the mold section on one side of the middle 95 of the mold have their flanges 6 presented in one direction whereas, the corresponding flanges to the other side of the middle of the mold are presented in the opposite direction, so that relative longitudinal movement in either direction is prevented. 100 105

A block 13 is disposed within the angle between the flanges 6 and 8 of each of the mold sections and these blocks are so positioned that the ones upon the upper mold section 5^a will be located at a point diametrically opposite to the ones upon the lower 110

mold section 5^c, the blocks upon the side sections 5^b of the mold being similarly diametrically oppositely located.

Each of the blocks 13 is formed with a threaded stud 14 which projects through an opening formed in the flange 8 with which the block is associated, and threaded upon the said stud of the block is a nut 15 which firmly holds the block in position in the angle between the flanges 6 and 8. Each block 13 is formed with a transversely extending aperture 16 and engaged through this aperture and through similar apertures 17 formed in spaced ears 18 at the outer end of an arm 19, is a pivot pin 20, the arms in this manner being pivotally connected with the said blocks and consequently with the flanges 6.

A head 24, to be presently more specifically described, is formed with pairs of lugs 22 through which and lugs 21 at the inner ends of the arms are passed pivot pins 23.

It will be understood from the foregoing description of the invention that one of the heads 24 is provided for each set of the arms 19 and through each of the heads there is formed, axially, a threaded bore 25 through which passes an adjusting rod 26 having right and left threads which extend from a point mid-way between the ends of the rod to the said ends thereof.

It will be understood, of course, that rotation of the rod in one direction will serve to seat or adjust the heads 24 away from each other and that rotation in the opposite direction will serve to adjust the heads toward each other upon the said rods and in order that said rotation of the rod may be readily accomplished, there is provided at one end 40 of the rod a handle 27.

From the foregoing description of the invention, it will be seen that when the adjusting rod 26 is so rotated as to adjust the heads toward each other, the outer ends or extremities of the arm 19 are bowed inwardly and carry with them the sections 5^a, 5^b, and 5^c of the mold, thereby contracting the mold and

permitting of its removal from the hardened material of the partly completed culvert. On the other hand, when the mold is to be set up for use, its sections are expanded by adjusting the heads away from each other and the mold is then disposed upon any suitable bed or foundation and the material which is to constitute the culvert is suitably packed about the mold and allowed to harden.

It will be observed from inspection of Fig. 3 of the drawings, that the inner end of each of the arms 19 is partly squared, as indicated by the numeral 28 so that when the arm has been adjusted to a position directly radially with respect to the adjusting rod 26, in which position the sections of the mold will be fully expanded, further movement of the arm cannot be accomplished except in a direction to contract the sections of the mold.

What is claimed is:—

A mold comprising a plurality of arcuate sections, flanged ribs upon the inner sides of the sections, an adjusting rod arranged axially of the mold, a head mounted upon the adjusting rod, arms pivoted to the head, blocks having threaded studs inserted through the flanges of the ribs, nuts threaded upon the studs, the arms being pivoted at their outer ends to the blocks, the arms supporting the sections for adjustment radially with respect to the rod, and means carried by the ribs of certain of the sections and engaging with the ribs of certain other of the sections whereby to hold the sections against relative longitudinal displacement, the said flanges of the ribs serving as a means for limiting the movement of the arms in one direction.

In testimony that I claim the foregoing as my own, I have hereto affixed my signature in the presence of two witnesses.

JOHN C. KNAPP, JR.
